FOLDING GOLF BAG CARRIER

William H. Jamieson and William H. Jamieson, Jr., Patchogue, N. Y.

Application April 20, 1950, Serial No. 156,988

2 Claims. (Cl. 280—41)

1

This invention relates to new and useful improvements in golf bag carriers.

A main object of the invention is to provide a bag carrier so compact, when folded, that it may be inserted within the golf bag with the clubs when not in use.

A further object is to provide a simple, efficient, durable carrier to which the bag may be readily attached and which, by a simple manipulation may be expanded to operative condition or contracted to inoperative condition at will and in a matter of a few seconds.

A further object is to provide a simple, efficient device to which a golf bag may be readily attached which has the above advantages and is light in weight and economical to produce thereby enabling it to be sold at reasonable cost.

Further and more specific objects, features and advantages will more clearly appear from a consideration of the detailed specification hereinafter set forth, especially when taken in connection with the accompanying drawings which illustrate a present preferred form which the invention may assume and which form part of the specification.

In brief and general terms, the invention includes an elongate frame to which the golf bag may be readily attached either by straps or hooks. This frame extends the whole length of the bag and the bag is attached to one face thereof. To the other face are pivoted a pair of legs adapted to extend normally downwardly in a divergent manner and having wheels at the bottom thereof. Links are connected at one end pivotally to the legs at an intermediate point thereon and these links are, at their other ends, pivotally connected to a slidable member which is slidably disposed and mounted on the frame. A manipulable element is connected to this slidable member to enable the person using the device to move the slidable member in one direction or another to expand the legs to operative position or to contract them to an inoperative position closely adjacent the length of the frame so as to permit the frame and associated parts to be easily inserted in the bag with the clubs when not in use.

A further feature includes bracing members associated with the links and slidably related to the legs to cause the bracing members to assume operative bracing position when the legs are expanded and to assume inoperative position when the legs are contracted.

A still further feature is a simple manipulable latching device operable automatically to latch the parts in operative position and to be manipulated to release the parts when they are to be

2

collapsed into close adjacency with the frame for storage within the bag.

A still further feature includes an elongate reinforcing strip disposed within the bag and firmly related thereto to stiffen the bag along its length where it is to be hooked to the carrier and this reinforcing member is provided with hooks enabling the bag to be readily and easily hooked on to the carrier supporting frame at will.

10 The present preferred forms which the invention may assume are illustrated in the drawings, of which,

Fig. 1 is a perspective view of the device in expanded operative condition;

15 Fig. 2 is an enlarged side elevation of the device in operative condition with the golf bag attached;

Fig. 3 is a rear elevation of the device in collapsed condition and with the bag removed;

20 Fig. 4 is a side elevation of the device as shown in Fig. 3;

Fig. 5 is a vertical longitudinal section along the line 5—5 of Fig. 2;

Fig. 6 is a vertical section taken along the line 6—6 of Fig. 5;

25 Fig. 7 is a vertical section taken through the golf bag showing the construction of the reinforcing strip and the hooks whereby the bag may be attached to the carrier; and

30 Fig. 8 is a partial perspective view of the lower end of the carrier frame whereon the bag may be attached by straps instead of hooks.

35 Referring now merely to the specific construction shown in the drawings, which illustrate the present preferred forms which the invention may assume, it is to be noted that the carrier comprises an elongate frame number 10 of U-shaped channel construction. The upper portion of this frame is provided with a housing or casing 11 to form an enclosed casing for the upper end of the frame.

40 Just below the enclosed housing 11 a bracket 12 is fixed to the rear of the frame 10 and has oppositely extending divergent arms 13 and 14 to which are pivoted respectively the upper ends 45 of leg members 15 and 16 to the lower ends of which are connected wheel elements 17 and 18. Since the legs are connected to the bracket 12 in a divergent manner, it is clear that when they are moved out away from the frame 10 they will

50 spread part and that when they are moved in toward the frame 10 they will tend to move together. The legs are thus moved out and drawn back by reason of the pivotal connection to them along their intermediate portions as at 19 and 55 20 of links 21 and 22 respectively.

The other ends of these links 21 and 22 are

pivotedly connected to a slide plate 23. This slide plate 23 is adapted to slide along the bottom of the U-shaped channel frame 10 and is held in place by extra side walls 24 and 25 which are welded to the inner faces of the side walls of the frame and the bottoms of these plates 24 and 25 are slightly spaced above the bottom of the frame to provide a space into which the edges of the slide plate 23 extend and in which it is held for sliding movement. The ends of the links 10 are connected to this slide plate 23 by means of their connection to a bracket 26 which is fastened to the rear face of this plate 23 as shown in Fig. 5.

At the upper end of the slide plate 23 there is connected a block 27 to which is connected a manipulable rod or stem 28 which extends up through and beyond the top of the housing 11 and can be grasped by the hand of the operator to move the slide plate 23 up and down with respect to the channel frame 10. The rod 28 is provided with a lateral pin or latch member 29 adapted to be engaged by a pivoted latch member or pawl 30 which is pivoted to a bracket 31 on the side of the housing 11 and is held in 15 pin engaging position by means of a spring 32. To the opposite end of the latch pawl there is connected a manipulable rod 33 which extends up beyond the top of the housing 11 and which when depressed releases the pawl from the pin as shown in Fig. 5. The pawl as shown is so disposed that when the rod 28 is moved up, the pawl and the pin are automatically engaged to hold the rod in upward position. To allow the rod 28 to be moved downward, the releasing stem 20 or rod 33 must be depressed by the operator thus 25 releasing the pawl.

Since the legs 15 and 16 are outwardly divergent, they are braced when expanded by means of bracing links 34 and 35, the upper ends of which are respectively pivoted at 36 and 37 to the legs 15 and 16 and at their lower ends are connected to sleeves 38 and 39 slidably surrounding the legs 15 and 16. These sleeves 38 and 39 are connected pivotally to short links 40 and 41, the other ends of which are pivotally fixed to an intermediate point on the links 21 and 22. As shown, these bracing links are respectively crossed between the legs as shown in Fig. 1 so that they tend to brace the legs in their divergent operative position and form a firm construction when thus expanded.

The bottom of the frame member 10 is bent around as shown at 42 to form a portion which may rest on the ground when the device is in use to hold it in upright position while the player is engaged in his game and leaves the device standing nearby. A bracing strut 43 is provided to keep this bent end from buckling. The frame 10 is provided with encircling collars 44 and 45 at spaced points throughout its length which extend around and are spaced from the front face of the frame 10 to provide sockets to receive certain hooks on the bag to be later described so as to easily permit the bag to be engaged with and disengaged from the support.

Since the golf bag is made of flexible non-rigid material, it must be reinforced along its inside wall along its length where it is to be supported from the carrier frame 10. To this end, there is disposed within the bag an elongate strip of metal 46 (Fig. 7) which at its lower end is provided with a series of apertures 47 and through these holes extend screw bolts 48 enabling this main strip 46 to be adjustably connected to an 70

extension piece 49 so as to permit this reinforcing means to be adjusted to bags of different lengths. Threaded stems 50 with wing nuts extend from plates 51 through the bag fabric to hold the fabric between themselves and the strip 46, and these plates 51 have hook elements 52 thereon extending downwardly and adapted to be disposed in the sockets on the collars 44 and 45 above mentioned. At the top of the bag there are two plates 51' with curved upper ends to grip between them the upper bead 53 usually found at the tops of golf bags. At the bottom of the bag there are two spaced plates 54 and 55 tightened by a screw stem 56 to grip the lower portion of the bag between them, the screw stem passing through the fabric of the bag at this point as at the other points above noted.

In the form of the invention shown in Fig. 8 the bag may be held on the front face of the frame 10 by means of straps 57 as shown.

In considering the operation of the device, it is to be noted that it mainly comprises an elongate frame which along one face is provided with sockets to receive the hooks on the bag above mentioned. Legs are pivotally related to the rear portion of this frame and extend downwardly and divergently and have wheels at their bottom. The legs normally lie close to the frame to permit them to be housed in the bag with the frame when the device is collapsed. Links are pivotally connected to the legs and at their other ends to a slidable element on the rear face of the frame. An operating rod is connected to this slidable member and is manipulable to cause the reciprocation of this slidable member or element up and down along the frame to cause the legs to be moved outwardly away from the frame to operative position and to be retracted or collapsed close to the frame when the slidable member is moved in the opposite direction. Bracing members are pivotally connected to the links and slidably related to the legs so as to brace them in their operative position when moved away from the frame. An automatic latch device is disposed on the frame to engage the manipulable rod to latch it in position to hold the legs in their operative position. A depressible stem is provided to release the latch at will when the legs are to be collapsed.

While the invention has been described in detail and shown with respect to the accompanying drawing, it is not to be limited to such details, since many changes and modifications may be made in the invention without departing from the spirit and scope thereof. Hence, it is desired to cover any and all forms and modifications of the invention which may come within the language and scope of any one or more of the appended claims.

We claim:

1. A golf bag carrier comprising a frame, wheeled legs pivoted to said frame, links pivotally connected to said legs, a slide plate slidably connected to said frame, said links being pivotally connected to said slide plate, a sleeve slidably connected to each of said legs, additional links pivotally connected to said sleeves and to said first-mentioned links, each leg having a bracing link pivotally connected thereto and pivotally connected to the sleeve connected to the other leg.

2. A golf bag carrier comprising a frame, wheeled legs pivoted to said frame, links connected at one end of the legs intermediate their length, a slidable plate mounted on said frame 75 to which plate the other ends of said links are

pivottally connected, a manipulable rod connected to said plate slidale in said frame and extending beyond the top thereof, a latch member mounted on said frame and engageable with a latch member mounted on said rod so as to engage the first mentioned latch member and maintain a relative position of said rod with respect to said frame, a releasing rod connected to one of said latch members and slidale in said frame to disengage said latch members.
